UNITED STATES PATENT OFFICE.

JASPER EARL NEWTON, OF YOAKUM, TEXAS.

DESIGN FOR A WATCH-DIAL.

45,201.

Specification for Design.

Patented Feb. 3, 1914.

Application filed September 3, 1913. Serial No. 788,007. Term of patent 7 years.

To all whom it may concern:

Be it known that I, JASPER EARL NEWTON, a citizen of the United States, residing at Yoakum, in the county of De Witt and State of Texas, have invented a new, original, and ornamental Design for Watch-Dials, of which the following is a specification, reference being had to the accompanying drawing, forming a part thereof.

The figure is a perspective view of a watch dial, showing my new design.

I claim:

The ornamental design for a watch dial, as shown.

JASPER EARL NEWTON.
